DESCRIPTION

FIG. 1 is an isometric view taken from the upper right front of a multipurpose tool including bypass pruner embodying our new design;

FIG. 2 is an isometric view taken from the lower left rear thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front elevational view thereof; and,

FIG. 8 is a rear elevational view thereof.

Folded tool blades are shown in broken line for illustrative purposes and form no part of the claimed design. The broken lines immediately adjacent to the shaded areas represent unclaimed boundaries of the design.
